UNITED STATES PATENT OFFICE.

WILLIAM H. BRITTON, OF MILFORD, AND OLNEY S. THAYER, OF BELLINGHAM, MASSACHUSETTS.

DESIGN FOR BRACKETS.

Specification forming part of Design No. 7,838, dated November 3, 1874; application filed June 1, 1874.
[Term of Patent 3½ years.]

To all whom it may concern:

Be it known that we, WILLIAM H. BRITTON, of Milford, county of Worcester and State of Massachusetts, and OLNEY S. THAYER, of Bellingham, county of Norfolk, State of Massachusetts, have invented a Design for Brackets, of which the following is a specification:

The nature of our design is fully represented by the drawing, in which A is the body or standard of the bracket, and B the shelf. The body A is flat, and in outline or form resembles a horn of plenty or cornucopia, having a long outwardly-sweeping curve, c, on one side, and a short outwardly-sweeping curve, b, on the opposite side, these curves terminating at their upper ends in the points e f. Between the point f and the table B the edge or outline d is convex, the opposite side,

x, of the bracket being nearly straight. The table B has straight sides; but the front consists of two curved projections, i i, as shown. The aperture z is designed for a screw in attaching the bracket to any proper support.

Having thus described our improvement, what we claim is—

A design for a bracket, the table of which has the curved projections i i, and the body of which, in its configuration, resembles a horn of plenty, having the curved edges b c, convex edge d, nearly straight side x, and points e f, substantially as described.

WILLIAM H. BRITTON.
OLNEY S. THAYER.
